CLAIM

The ornamental design for a shoe outsole bottom, as shown and described.

DESCRIPTION

FIG. 1 is a front perspective view of a shoe outsole bottom in accordance with my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dot-dash lines in the drawing views show the boundaries of the claimed design in the locations in which they are shown. The consistent length broken lines show environment in the form of a shoe upper and midsole periphery as well as portions of the shoe outsole bottom that form no part of the claimed design. The broken lines and structure they depict form no part of the claimed design.
